DESIGN FOR A TEXTILE FABRIC

Jean Frank Hoffmann, Los Angeles, Calif.

Application January 22, 1945, Serial No. 117,528

Term of patent 7 years

(Cl. D92—1)

To all whom it may concern:

Be it known that I, Jean Frank Hoffmann, a citizen of the United States, residing in the city of Los Angeles, in the county of Los Angeles and State of California, have invented a new, original, and ornamental Design for a Textile Fabric, of which the following is a specification, reference being had to the accompanying drawing, forming part thereof.

The figure is a plan view of a textile fabric showing my new design. The dot and dash lines

on the drawing outline a design unit, which unit is repeated in regular succession as indicated by the extensions beyond the unit boundaries.

The textile fabric of the present design is characterized by the specific representations of the sombreros arranged in the specific manner shown on the drawing.

I claim:

The ornamental design for a textile fabric, substantially as shown and described.
